UNITED STATES PATENT OFFICE.

BENJAMIN V. GILMORE, OF GAULEY BRIDGE, WEST VIRGINIA, ASSIGNOR TO JOHN W. GRAHAM, JAMES A. GRAHAM, AND WILLIAM S. PECK, ALL OF HINTON, WEST VIRGINIA.

HINGE JOINT FOR CONVERTIBLE ROADSTER SECTIONS.

Application filed March 29, 1921. Serial No. 456,595.

To all whom it may concern:

Be it known that I, BENJAMIN V. GILMORE, a citizen of the United States, residing at Gauley Bridge, in the county of Fayette and State of West Virginia, have invented certain new and useful Improvements in Hinge Joints for Convertible Roadster Sections, of which the following is a specification.

10 This invention relates to hinge joints for convertible roadster sections and has as its general object to provide a hinge joint especially useful in a structure such as illustrated and described in my Patent No.

15 1363405, Dec. 28, 1920.

More specifically, the invention has as its object to provide a hinge joint which will be exceptionally strong and durable and which will relieve the sideboards of the convertible 20 sections of strain, to a great extent, and which will more securely and firmly support and retain the sections in their different positions of adjustment.

Another object of the invention is to so 25 construct the joint that it will constitute a means for positively limiting the movement of the sections which it connects so that the sections when adjusted to one position or another will be caused to assume a correct relation to each other, that is to say in properly aligned or in properly folded relation.

In the accompanying drawings:

Figure 1 is a side elevation of a convertible roadster in the construction of which the 35 hinge embodying the invention is employed;

Figure 2 is a detail horizontal sectional view through the hinge joint;

Figure 3 is a perspective view illustrating two of the sections which are to be connected 40 by the joint and upon which the members of the joint are secured;

Figure 4 is a detail vertical transverse sectional view taken axially through the joint;

Figure 5 is a side elevation of one of the sections of the joint, the other section being shown in dotted lines and one element thereof in vertical section.

In the drawings the numeral 1 indicates 50 in general the body of a Ford runabout and 2 the rear portion of the chassis frame from which the ordinary tonneau has been removed. The convertible tonneau forming

the subject matter of my above-mentioned co-pending application and which is illustrated in general in Figure 1 of the present drawings, comprises a relatively fixed body section which is indicated in general by the numeral 3 and which consists of a bottom or floor 4 which is bolted or otherwise secured to the said portion 2 of the chassis frame, and sides 5 which upstand from the said bottom or floor 4. In addition to the fixed section 3, the tonneau includes a section 55 which is indicated in general by the numeral 6 and which is to constitute a portion of the rear part of the truck body when the tonneau as a whole is so converted, and this section comprises sides which are indicated by the numeral 7 and a bottom which is indicated by the numeral 8. It will be noted by reference to the drawings, that the hinge joint embodying the present invention is 60 designed to connect the ends of the sides 5 and 7 of the sections 3 and 6 of the convertible 65 tonneau so that the section 6 may be swung 70 forwardly to a folded position as illustrated in dotted lines in Figure 1 of the drawings or rearwardly to extend in alignment with the section 3 and thus constitute the rear end 75 of a truck body.

One member of the hinge joint of the invention is secured to the inner face of each side 5 of the section 3 of the tonneau and is indicated in general by the numeral 9, and this member comprises a circular flat-sided plate 10 secured by screws or other suitable fastening elements 11 to the said face of the respective side 5, as best shown in Figures 2, 3 and 4 of the drawings. The said plate 10 is provided centrally with an opening 12 which is in registration with an opening 13 formed in the said side 5, and these openings receive the shank of a bolt 14 which constitutes the pintle of the hinge joint. At 85 this point it may be stated that if desired instead of providing a bolt 14, the plate 10 may be formed centrally upon its inner face with an inwardly projecting threaded stud, although the bolt is to be preferred as it 90 may be readily replaced should it become broken. For a purpose to be presently described, the said plate 10 is formed upon its inner face near its periphery with an inwardly projecting relatively short stud indicated by the numeral 15.

The other member of the hinge joint is indicated in general by the numeral 16 and the same likewise comprises a flat-sided circular plate which is indicated by the numeral 5 17 and which is secured by screws or other suitable fastening elements 18 to the outer face of the respective side 7 of the section 6 of the tonneau. An opening 19 is formed centrally in the plate 17, and an opening 10 20 of larger diameter is formed in the side 7 of the tonneau section 6, the bolt 14 being fitted through the opening 19, and nuts 21 being threaded onto the said bolt and housed within the opening 20 in the manner best 15 illustrated in Figure 4 of the drawings. The plate 17 is formed concentric to the opening 19 with an arcuate semi-circular slot 22 which is of a width slightly greater than the diameter of the stud 15 so as to receive the 20 said stud in the manner shown in Figures 2, 4 and 5. A groove 23 is formed in the outer face of the side 7 and is in registration with the slot 22 so that the stud 15, being of a length greater than the thickness 25 of the plate 17, will nevertheless be accommodated. It will now be evident that the section 6 of the tonneau may be swung forwardly upon the bolt 14 to assume a position partly or wholly housed within the section 30 3 of the tonneau in which position of the section the stud 15 of the hinge members 9 will seat in the lower end of the slot 22 in the respective member 16, or the section 6 may be swung rearwardly so as to extend 35 rearwardly in alignment with the section 3, as shown in Figures 1 and 2 of the drawings, in which relative position of the sections, the said studs will seat in the upper ends of the respective slots and by engaging the end 40 walls of the slot, will securely brace the sections in their relative position, and more especially the section 6. It will also be evident that the plate comprising the members of the hinge joint serve also as wear plates so 45 as to prevent undue wear of the sides of the tonneau sections.

As illustrated in Figures 2 and 5 of the drawings, the sections of the tonneau are preferably so arranged and connected that 50 when the section 6 is in alignment with the section 3 to complete the truck body, the forward edge of its floor 8 will rest or abut against the rear edge of the floor 4 of the

section 3 so that the parts are additionally braced in the relation stated. 55

Having thus described the invention, what is claimed as new is:

1. The combination with a fixed tonneau section and a section pivotally adjustable with relation thereto, the said sections having wooden floors and side walls, of means pivotally connecting the side walls and comprising circular flat relatively thin plates of uniform thickness secured upon the confronting faces of the side walls, the plates and walls having aligned central openings, a pivot element fitted through the openings, one of the plates having an arcuate slot concentric to the opening and the adjacent wall, a groove registering with said slot, and a stud upon the other plate working in the slot and the groove, the pivot element comprising a bolt and a nut threaded onto the end of the bolt and housed within the opening in one of said walls, the adjacent edges of said floors being adapted to abut when said adjustable section is in open position. 60

2. The combination with a fixed tonneau section and an adjustable section of a hinge construction for said sections: said sections each including a wooden floor and side walls; said hinge construction comprising thin, smooth-faced metal plates rigidly secured on the confronting faces of said side walls, said plates each having a central aperture, and a pintle lodged in one of said side walls and reaching through said aperture, a nut threaded on the end of said pintle and housed within an opening provided in the other of said side walls; one of said plates having a slot running concentrically with the axis of said pintle and being of semi-circular extension, a groove being formed in the corresponding side walls, of the same width and extension as said slot, a stud rigidly secured in the other of said plates and adapted to engage in said slot and groove; the adjacent edges of said floors being adapted to abut when said adjustable section is in open position, thereby forming a stop co-operating with said slots and grooves to limit the swinging of said adjustable section in one direction. 70

In testimony whereof I affix my signature.

BENJAMIN V. GILMORE. [L.S.]
